(57) **CLAIM**

The ornamental design for a portable beverage holder, as shown and described.

DESCRIPTION

FIG. 1 is a top plan view of a portable beverage holder showing my new design;

FIG. 2 is a bottom plan view thereof;

FIG. 3 is a side elevational view thereof;

FIG. 4 is a rear elevational view thereof; and,

FIG. 5 is a perspective view thereof.

The broken lines are for illustrative purposes only and form no part of the claimed design.
